UNITED STATES PATENT OFFICE.

LEWIS WARRINGTON CHUBB, OF EDGEWOOD PARK, PENNSYLVANIA, ASSIGNOR TO
WESTINGHOUSE ELECTRIC & MANUFACTURING COMPANY, A CORPORATION OF
PENNSYLVANIA.

ELECTRON-TUBE OSCILLATOR.

Application filed February 14, 1921. Serial No. 444,636.

To all whom it may concern:

Be it known that I, LEWIS WARRINGTON CHUBB, a citizen of the United States, and a resident of Edgewood Park, in the county of Allegheny and State of Pennsylvania, have invented a new and useful Improvement in Electron-Tube Oscillators, of which the following is a specification.

My invention relates to wireless transmission systems and particularly to vacuum-tube oscillation generators employed in connection with such systems.

The object of my invention is to provide an oscillation generator of the above-indicated character that shall be simple in construction, reliable in operation and of a higher efficiency than has heretofore been obtained in such tubes.

In the present type of vacuum tube employing a single anode, a limiting feature in the design of the tube is the maximum operating temperature of the anode.

As is well known, a large portion of the energy supplied to the plate-filament circuit is lost as heat at the anode. At present, by reason of the large heat losses incurred, the maximum operating efficiency of the three-electrode vacuum-tube is approximately 50%. This means that practically one half the energy supplied to the vacuum tube is lost as heat at the anode.

The maximum temperature at which the material constituting the anode may be operated is limited first; by the melting point of the material and second; by the rate of evaporation of the material.

According to my invention, I provide an oscillation generator in which a plurality of anodes are employed to reduce the working temperature of the individual anodes, thereby permitting a greater energy input to the vacuum tube without undue heating.

Briefly speaking, my invention comprises a plurality of plate elements, a source of electron emission and means included in an oscillatory circuit whereby an electron stream may be selectively controlled to impinge upon predetermined groups of the plate elements to cause the oscillations in the oscillatory circuit to be sustained.

My invention may best be understood by reference to the accompanying drawings, in which:

Fig. 1 is a diagrammatic view of circuits and apparatus embodying my invention. 55

Fig. 2 is a view, partially diagrammatic and partially structural, showing my invention as applied to a wireless-transmission system.

Referring to Fig. 1, an oscillation generator 1 comprises an electron-emitting cathode 2 and a plurality of curved anode elements or plates 3 and 4 which are disposed alternately around the inside periphery of the vacuum-tube device 1 and are inclined in opposite directions with respect to a line connecting the cathode 2 with the respective anode elements 3 and 4. The anode elements 3 and 4 are connected in parallel relation by means of conductors 5 and 6, respectively. 60 The hot cathode 2 may be energized by means of a battery 7 through a resistor 8. 65

A high-frequency oscillatory circuit, which is connected in shunt relation to the groups of plate elements 3 and 4, comprises 75 a variable capacitance 9, an inductance coil 11 and a balance coil 12. The inductance coil 11 is so disposed that the magnetic field therefrom is transverse to the electro path, and the intensity of the magnetic field, at 80 the surface of the hot cathode 2, is substantially zero.

An electrostatic field is produced between the hot cathode 2 and the plurality of plate elements 3 and 4 by means of a source of 85 energy 13 which is included in a circuit that extends from the hot cathode 2 to the plurality of plate elements 3 and 4 through a conductor 14, the source of energy 13, a balance coil 12 and the conductors 5 and 6, 90 respectively.

Referring to Fig. 2, the arrangement shown differs from that of Fig. 1 by reason of the fact that the capacitance of the condenser 9 is replaced by that of an antenna 95 15. In this arrangement, I have shown the coil 11 so disposed as to produce a transverse magnetic field that is substantially zero at the surface of the hot cathode 2. The oscillatory circuit includes the antenna 15, a 100

variable inductance coil 16, the inductance coil 11, the balance coil 12 and a ground lead 17.

In the operation of my invention, I utilize the well known effect of a transverse magnetic field upon the path of an electron stream. In a vacuum-tube device comprising a central filament and a co-axially mounted anode, the electrons emitted from the heated filament travel in substantially straight lines to the surface of the anode. Upon impressing a transverse magnetic field upon the electron path, the path of the electrons becomes curved, the degree of curvature depending upon the intensity of the transverse magnetic field. Thus, with a sufficiently strong transverse magnetic field, the electron path may be so bent that alternate anodes will shield the remaining anodes from the electron stream.

I have found that, by reducing the magnetic field in the space immediately surrounding the cathode to substantially zero, the electrons are permitted to attain such velocity that, upon entering the magnetic field, the effect thereof is not sufficient to cause the electrons to return to the cathode.

In operation, upon impressing a transverse magnetic field upon a portion of the electron path, the electrons pass radially outwardly from the surface of the hot cathode until they enter the magnetic field, whereupon the path of the electron is curved to cause it to strike one of the groups of anode elements 3 and 4. Such a path may be indicated by the dotted lines 18 of Fig. 1, in which the electrons are caused to strike anodes 3.

Upon a reversal of the magnetic field, the path of the electrons, upon entering the region of the magnetic field, is curved in the opposite direction to cause the electrons to impinge upon the opposite group of anode elements 4. This path is represented by the dotted lines 19 in Fig. 1.

Thus, it can be seen that, with the phase of the magnetic field and plate-filament current adjusted properly, the direction of the plate-filament current through the balance coil may be such as to establish and maintain an alternating current in the oscillatory circuit.

From the foregoing description, it will be observed that the advantage of my invention resides in the provision of an oscillation-generator system in which the customary anode losses may be distributed among the plurality of anodes, thus permitting the construction of a high-power vacuum-tube device of relatively small dimensions.

While I have shown only one embodiment of my invention, it is capable of various other modifications without departing from the spirit and scope of my invention. I desire, therefore, that only such limitations

shall be placed thereon as are indicated in the appended claims.

I claim as my invention:

1. An oscillation generator comprising an evacuated vessel, a plurality of plate elements electrically connected, a second plurality of plate elements electrically connected to one another and arranged to alternate with the plate elements of the first plurality, an oscillatory circuit connecting one of said pluralities to the other, a cathode, means for establishing an electrostatic field between said cathode and said anodes, whereby a space current is created in said vessel, and means operatively associated with said oscillatory circuit for directing the space current alternately from one plurality of plate elements to the other. 75

2. An oscillation generator comprising an evacuated vessel, a plurality of plate elements electrically connected, a second plurality of plate elements electrically connected to one another and arranged to alternate with the plate elements of the first plurality, an oscillatory circuit including separate, 90 serially-connected, inductance and capacitance devices and connecting one of said pluralities to the other, a cathode, and means for establishing an electrostatic field between said cathode and said anodes, whereby a space current is created in said vessel, certain of said serially connected devices being operatively associated with said evacuated vessel to modulate said space current. 95

3. An oscillation-generator system comprising an evacuated vessel, a plurality of plate elements connected in parallel relation, a second plurality of plate elements also connected in parallel relation, the plates in the two groups being arranged alternately, a cathode for supplying a space current thereto, a circuit including inductance, a second circuit including inductance and capacitance, both circuits being in parallel and shunted across said first and second plurality of plate elements, and means for producing an electrostatic field between said plate elements and said cathode. 105

4. In a vacuum-tube device, the combination with a plurality of juxtaposed plate elements, of a cathode for supplying a space-current stream, means for connecting alternate plate elements in parallel in two groups, and means whereby said space-current stream may be selectively controlled to impinge upon predetermined groups of said plate elements. 115

5. In a vacuum-tube device, the combination with a plurality of juxtaposed plate elements, of a source of electron emission, an oscillatory circuit and means included in said oscillatory circuit whereby said electron emission may be selectively controlled to impinge upon predetermined groups of separate 125

rated plate elements to cause said vacuum-tube device to function as an oscillation generator.

6. In a vacuum-tube device, the combination with a plurality of juxtaposed plate elements, of a source of electron emission, means for causing an electrostatic field between said plurality of plate elements and said electron source and means whereby said electron stream may be selectively controlled to impinge successively upon predetermined groups of separated plate elements to cause said vacuum-tube device to function as an oscillation generator.
7. In a vacuum-tube oscillation generator, the combination with a source of electron emission, of a plurality of plate elements disposed annularly thereabout, alternate plate elements being connected in parallel, means for producing an electrostatic field between said electron source and said groups of parallel connected plate elements, an oscillatory circuit including capacitance and an inductor shunted across said groups of plate elements, said inductor being disposed to produce a magnetic field transverse to the electron paths and transverse to straight lines joining successive plate elements, and said field being of substantially zero value in a region closely adjacent to said electron source and of a maximum value in the surrounding region, whereby said electron stream may be selectively controlled.
8. An electron-tube device comprising an evacuated container, a plurality of anodes and a cathode disposed within said evacuated container and means for producing a magnetic field near the anodes, said field being transverse to the plane containing said cathode and said plate elements, and said means being so disposed that the magnetic field at the surface of the cathode is substantially less than in the region of said anodes.
9. The combination with an electron-emitting cathode, of a pair of plates for receiving an electron stream therefrom, said plates being disposed at opposite angles with respect to a straight line drawn to the cathode, and means for deflecting said electron stream to cause the same to impinge more directly upon the one or the other of said inclined plates.
10. The combination with an electron-emitting cathode, of a pair of plates for receiving an electron stream therefrom, one of said plates being disposed at an angle with respect to a straight line connecting said plate with said cathode, and means for deflecting said electron stream to cause the same to impinge more directly upon said inclined plate, the other plate being arranged in such position as to be shielded by said inclined plate when said stream is deflected.
11. The combination with an electron-
- emitting cathode, of a plurality of annularly disposed plates associated therewith, alternate plates being connected in parallel, and successive plates being inclined at opposite angles with respect to their respective radial lines, and means for deflecting said electron stream to cause the same to impinge more directly upon the one or the other of said groups of parallel-connected inclined plates.
12. The combination with an electron-emitting cathode, of two groups of alternately disposed plates for receiving an electron stream therefrom, the plates of one of said groups being disposed at an angle with respect to a straight line connecting said cathode with said plates respectively, and means for deflecting said electron stream to cause the same to impinge more directly upon the inclined plates of said last-mentioned group, the plates of the other group being arranged in such position as to be shielded by said inclined plates when said stream is deflected.
13. The combination with an electron-emitting cathode, of two groups of alternately disposed plates for receiving an electron stream therefrom, the plates of the respective groups being inclined in opposite directions with respect to a straight line connecting said cathode with said plates respectively, and means for deflecting said electron stream to cause the same to impinge more directly upon one or the other of said groups of inclined plates, the plates being so arranged that the plates of one group are shielded by the plates of the other group when said stream is deflected.
14. The combination with an electron-emitting cathode, of a plurality of annularly disposed plates associated therewith, alternate plates being connected in parallel, and means, including an annular coil parallel to the plane of said plurality of annularly disposed plates and a smaller concentric coil carrying current in the direction opposite to the current in said annular coil, for alternately strengthening and weakening the space current flowing to the two groups of parallel-connected plates.
15. The combination with an electron-emitting cathode, of a plurality of annularly disposed plates associated therewith, alternate plates being connected in parallel, and successive plates being inclined at opposite angles with respect to their respective radial lines, and means, including an annular coil parallel to the plane of said plurality of annularly disposed plates and a smaller concentric coil carrying current in the direction opposite to the current in said annular coil, for alternately strengthening and weakening the space current flowing to the two groups of parallel-connected plates.
16. The combination with an electron-

- 4
- emitting cathode, of a pair of plates for receiving an electron stream therefrom, said plates being so disposed that each protects at least a part of the other from electrons moving toward the protecting plate, a tuned oscillation circuit serially associated with said plates, and means responsive to said oscillation circuit for deflecting said electron stream to cause the same to impinge more directly upon the one or the other of said inclined plates.
17. In a vacuum-tube oscillation generator, the combination with a source of electron emission, of a plurality of plate elements disposed annularly thereabout, alternate plate elements being connected in parallel, and successive plates being inclined at opposite angles with respect to their respective radial lines, a tuned oscillation circuit serially associated with said plates, and means responsive to said oscillation circuit for producing a transverse magnetic field which is relatively strong in the annular region of said plate elements and relatively weak near said electron source, whereby said electron stream may be alternately deflected to impinge more directly upon the one or the other of said groups of inclined plates.
18. In a vacuum-tube oscillation generator, the combination with a source of electron emission, of a plurality of plate elements disposed annularly thereabout, alternate plate elements being connected in parallel, and successive plates being inclined at opposite angles with respect to their respective radial lines, an oscillatory circuit shunted across said groups of parallel-connected plate elements, said circuit including an inductor and a condenser, a coil also shunted across said plate elements, and means associated with said coil for causing an electrostatic field between said plurality of plate elements and said cathode, said inductor comprising an annular coil parallel to the plane of said

plurality of annularly disposed plates and a smaller concentric coil carrying current in the direction opposite to the current in said annular coil for alternately strengthening and weakening the space current flowing to the two groups of parallel-connected plates.

19. In a device of the class described, a disk-shaped evacuated vessel, means for producing a space current therein, and means adjacent the faces thereof for producing a field therein for controlling said space current.

20. In a space-current device, a plurality of electrodes arranged in an annular row in pairs, each pair converging inwardly.

21. In a space-current device, a plurality of electrodes arranged in an annular row in pairs, each pair converging inwardly and a source of electrons within the annulus.

22. In a space-current device, a plurality of electrodes arranged in an annular row in pairs, each pair converging inwardly and a source of electrons within the annulus, corresponding members of the several pairs being electrically connected.

23. In a space-current device, a plurality of electrodes arranged in an annular row in pairs, each pair converging inwardly, a source of electrons within the annulus, corresponding members of the several pairs being electrically connected, and means for directing the electrons against the faces of the electrodes away from the other member in each pair.

24. In combination, a vessel and means for producing therein a magnetic field progressively changing in intensity from the middle toward the periphery of the cross-section thereof.

In testimony whereof, I have hereunto subscribed my name this 8th day of February, 1921.

LEWIS WARRINGTON CHUBB.
